REFRIGERATING APPARATUS

Lonzo S. Cooper, Piqua, Ohio, assignor to General Motors Corporation, Dayton, Ohio, a corporation of Delaware

Application September 30, 1936, Serial No. 103,280

3 Claims. (Cl. 137—139)

This invention relates to refrigerating apparatus and more particularly to valve means for refrigerating apparatus.

Refrigerator manufacturers naturally desire that their refrigerating systems be serviced by their own service organizations. Heretofore they have been unable to accomplish this since anyone could, if called upon, service a refrigerating system. In some cases individuals would lead the public to believe that they were authorized service men when in fact they were not.

It is an object of my invention to provide a means whereby unauthorized servicing of refrigerating systems may be hindered or prevented.

It is another object of my invention to provide a valve means for a refrigerating system which can only be used by one having a particular form of means for its operation.

It is another object of my invention to provide a sealed valve means for a refrigerating system which may be operated by a portable external electromagnetic means capable of moving the valve to open or closed position.

Further objects and advantages of the present invention will be apparent from the following description, reference being had to the accompanying drawing, wherein a preferred form of the present invention is clearly shown.

In the drawing:

Fig. 1 is a diagrammatic view of the refrigerating system embodying my invention;

Fig. 2 is a vertical sectional view through the refrigerant shut off valve embodying my invention;

Fig. 3 is another vertical sectional view of the liquid valve embodying my invention; and

Fig. 4 is a top view of the valve with the cover and electromagnetic means removed.

Briefly, I have disclosed a refrigerating system of the compression type provided with a shut off liquid line valve sealed within rigid walls. This valve is provided with a bar of magnetic material which may be attracted and rotated by an electromagnet operated and located outside of the rigid walls of the valve. This bar may be attracted and turned to position where it rests upon shoulders to hold the valve in the open position when desired or the electromagnetic means may be used to attract the bar and to rotate the bar to another position where it rests within a notch which permits the valve to be moved to closed position. The electromagnet must have two poles which fit within a recess within the top of the valve casing and must have adequate strength for attracting the bar of magnetic material within the

valve casing. Such an electromagnet must be of special manufacture and would be difficult for an unauthorized service man to acquire. Since in servicing refrigeration equipment it is usually necessary to close the valve in the liquid line, this would prevent many unauthorized service men from servicing refrigerating equipment provided with this valve.

Referring now to the drawing and more particularly to Fig. 1 there is shown a refrigerating system including a compressor 20 driven by an electric motor 22 for compressing the refrigerant and for forwarding the compressed refrigerant to a condenser 24 where the compressed refrigerant is liquefied and collected in the receiver 26. From the receiver 26 the liquid refrigerant is forwarded through a supply conduit 28 to an expansion valve 30 which controls the flow of refrigerant into an evaporating means 32. Within the evaporating means, the refrigerant evaporates and absorbs heat from compartment 34 which is to be cooled. This refrigerant is returned to the compressor through a conduit 36. The operation of the motor-compressor unit is controlled by a snap acting switch means 38 operated in accordance with the temperature of the thermostatic bulb 40 mounted upon the evaporating means 32. While this refrigerating system is illustrated as the preferred form, other refrigerating systems may be employed.

Connected into the liquid line 28 is a improved form of shut off valve designated by reference character 42. This valve is provided with a valve body formed of rigid walls which entirely enclose the valve proper. This valve is provided with a cylindrical casing 44 provided with an inlet 46 and an outlet 48. Within this casing is a valve chamber 50 and a passage 52 leads from the inlet 46 to chamber 50 and a second passage 54 leads from the chamber 50 to the outlet 48. A portion of the passage 54 adjacent the valve chamber 50 serves as a valve seat. The top of the member 44 is closed by a top plate 56 containing a recess 58. This top plate is provided with a heavy peripheral flange and a relatively thin center wall. Beneath this thin center wall is a second chamber 60 formed in the valve body. In the lower portion of this chamber 60 is a round aperture plate 62 which is fastened to the member 44 by four screws designated by the reference character 64. Two lugs of shoulders 66 are also provided on top of this plate 62. All of these parts are preferably made of brass or some other non-magnetic material.

With the valve chamber 50 is a valve 68 pref-

erably of stainless steel. This valve is provided with a conically pointed lower end which is adapted to close the mouth of the outlet passage 54. This valve 68 is provided with a shoulder 70 which surrounds a lower spring retainer 72. This lower spring retainer 72 serves to guide the lower end of the valve within the valve chamber 50 and also supports the lower end of a compression type spring 74 which may be made of Monel or spring 10 brass. The upper portion of this spring is supported by an upper spring retainer 76 which in turn is supported by a ball race 78. This ball race or ball bearing is supported by the plate 62.

The plate 62 is provided with an aperture which 15 receives the upper portion of the valve stem. This upper portion of the valve stem is provided with a reduced threaded portion to which is threaded a flat bar 80 of magnetic material. This bar 80 is adapted to rest in the grooved or 20 notched portion between the shoulders or lugs 66 when the valve is in closed position. When the valve is in open position this bar is first raised and then turned from 45 to 90 degrees so that it rests upon the shoulders 66, thereby 25 holding the valve in open position against the tension of the spring 74. The upper end of the valve stem may be provided with a rounded raised hump or point 84 for engaging the top member so as to permit the easy rotation of the 30 bar 80 and the valve stem which is also facilitated by the ball race. This hump 84 serves to prevent the bar 80 from being drawn tightly against the top member 66 and also serves as a pivot. The ball race permits the spring 74 to 35 turn freely with the valve.

Above the top plate is an electromagnet generally designated by the reference character 86. This electromagnet has two poles 88 and 90 which just fit within the recess 86 and the top 56. 40 These two poles 88 and 90 form the lower ends of the magnetic core upon which is wound the magnetic coils 92 and 94. These coils are supplied with electric energy from an external source usually the common electric light circuit through 45 the electric conductor 96. One of the conductors 98 extends through the coil 94 while the other extends through a binding post 102 which supports a spring contact 104. This spring contact 104 makes contact with a cooperating contact 50 106 on the post 108 extending upwardly from the core 88. This contact is connected to the electromagnet coil 92 which in turn is connected at its lower end to the lower end of the coil 94. A push button 110 is provided at the top of the electromagnet for engaging the spring contact 104 for 55 closing the electric circuit 92.

In the normal operation of the refrigerating system the valve 42 always remains in the open position with the bar 80 resting upon the shoulders or lugs 66. This holds the valve 68 away from the mouth of the passage 64 so that refrigerant is permitted to flow from the inlet through the passage 52 into the valve chamber 50 and through the passage 54 to the outlet 48. 60 The top member of the valve is preferably marked to show the position for which the electromagnet must be placed and moved to first attract the bar 80 and then to turn the bar to open or closed position as desired.

70 When it is desired to open the valve, the electromagnet is placed with its two poles directly above the two ends of the bar 80. The push button 110 is then pushed to close the circuit and to cause electric energy to flow through the electromagnet coils 92 and 94 to provide a powerful elec-

tromagnetic force or attraction tending to pull the bar 80 upwardly from its position between the shoulders 66. This pulls the bar 80 upwardly until the hump 84 rests against the top wall 56. Then while the push button 110 is still 10 pushed downwardly to keep the electromagnet energized, the electromagnet is turned to the position indicated on the top of the plate as being the open position. In this case the electromagnet is turned from closed position to open position so 15 that the bar is moved from its position between the shoulders 66 and turned to the position above the shoulders 66 and then the push button 110 is released to permit the bar 80 to drop onto the shoulders 66 and the valve 68 is thereby moved 15 to open position. All this is accomplished without any mechanical connection between the valve and the electromagnet outside of the valve body.

In order to move the valve from open position to closed position, the poles of the electromagnet are placed directly above the bar 80 and the push button 110 is depressed to energize the electromagnet and raise the bar 80 to its upward position and then continuing to depress the push button, the electromagnet is turned until the bar 80 is between the shoulders or lugs 66 after which the push button is released to allow the bar to move downwardly under the force of the spring 74 onto the shoulders or lugs 66 which 30 places the valve in open position.

In order to service a refrigerating system, it is ordinarily necessary to close the valve in the liquid line. Thus, unless a service man has an electromagnet capable of fitting the top of the valve 35 and sufficiently powerful to attract and turn the bar 80 as required, the liquid line cannot be closed and therefore it cannot be ordinarily serviced by someone not having the proper equipment.

While this valve is shown applied to a refrigerating system, for the purpose of illustrating the invention, it obviously could be applied to numerous other fluid systems and conduits, particularly where it is desired to provide a valve which cannot be tampered or disturbed by the general 45 public. The valve has no external openings and no packing of any kind is required, thus eliminating a major source of trouble.

While the form of embodiment of the invention as herein disclosed, constitutes a preferred 50 form, it is to be understood that other forms might be adopted, all coming within the scope of the claims which follow.

What is claimed is as follows:

1. A valve means including a sealed valve body 55 with rigid walls containing and completely enclosing a valve sealed therein, said valve being provided with a portion of magnetic material, said valve consisting of a bar rotatable with respect to the valve body, said valve having open and closed positions, said valve body having a shoulder for supporting the bar when the valve is in the open position and a notch adjacent the shoulder for receiving the bar when the valve is in closed position, said magnetic portion being moved by magnetic means outside the valve body to move the valve and the bar from one position to another.

2. A valve means including a sealed valve body having a face exposed to the atmosphere, a valve 70 completely enclosed by said body, said valve including a portion formed of magnetic material, said valve being rotatably mounted with respect to the valve body, magnetic means normally independent of said valve means and movable into 75

position opposite said exposed face, said magnetic means, when in position opposite said face operating upon said magnetic portion to rotate and lift said valve, and means for holding the valve in either an open or closed position.

5. A valve means including a sealed valve body having a face exposed to the atmosphere, a valve completely enclosed by said body, said valve in-

cluding a portion formed of magnetic material, magnetic means normally independent of said valve means and movable into position opposite said exposed face, said magnetic means, when in position opposite said face operating upon said magnetic portion to cause movement of said valve.
